TERMINAL CONNECTOR

William S. Thomas, Williamsport, Pa., assignor,
by mesne assignments, to Peter Zayac, Johnson
City, Joseph Marconi, Endicott, and Henry C.
Schloer, Vestal, N. Y., a partnership

Application October 19, 1948, Serial No. 55,360

3 Claims. (Cl. 173—259)

1

This invention deals with terminal connectors of the type commonly employed in anchoring one end of a cable to the terminal post of a battery and is concerned primarily with a connector which is capable of withstanding high pressure as it is clamped about the post.

To the end of clearly setting forth the objects and advantages of the present invention, reference is made to the co-pending application of William S. Thomas, Serial Number 7,173, filed February 9, 1948, and entitled "Battery Terminal Connector." In this application there is disclosed a connector which is intended to be improved by the present invention.

Briefly referring to certain salient features of said connector it is noted that the connector is designed for positive actuation both in clamping the jaws of the connector about a terminal post and in loosening the jaws from the post.

To provide this positive actuation, the connector is formed with a pair of complementary jaws having confronting recesses which define the opening that receives the battery post. The main body portion of the jaws is made from an appropriate metallic alloy which is fairly soft and which has the desired noncorrosive properties. Adjacent to the free end of each jaw there is imbedded therein a bushing of hard metal such as steel. These bushings are oppositely threaded and coacting therewith is a screw stem which is oppositely threaded for the respective bushings. This stem may be rotated in one direction to draw the jaws together with a positive actuation and in an opposite direction to spread the jaws with an equally positive actuation.

It happens that connectors of the type aforesaid are largely used in conjunction with the batteries and cables of motor vehicles. The mechanics and workmen who anchor the connectors to the battery posts are prompted by desire to make certain that the connector is securely clamped to the post. Due to their zeal they often apply such force to the screw stem which is increased by the mechanical advantage of the threads to rupture the jaws at a zone closely adjacent to the steel bushings.

With this condition in mind, the present invention has in view as its foremost objective the provision of a terminal connection of the type indicated which includes soft metallic jaws of an alloy with hard metal bushings imbedded therein together with means for reinforcing the jaws in the zones adjacent to the bushing.

More in detail, the invention has as an object the provision, in a connector of the type indi-

2

cated, of a reinforcing element in the form of a steel band which has one end anchored to one of the bushings and which extends through the jaw structure.

In carrying out this idea in a practical embodiment, it has been found desirable to integrally connect the reinforcing element for one jaw with the reinforcing element of the other jaw. Thus, a further object is to provide, in a connector of the character noted, a reinforcing member which takes the form of a U-shaped band that is imbedded in the jaw structure about the battery post opening and each free end of which is anchored to the bushing in each of the respective jaws.

From the foregoing it is apparent that in order for the reinforcing member to function properly it is necessary that each end thereof be securely anchored to the respective bushing. Thus, another object is to provide, in a connector of the type indicated, an effective connection between each free end of the jaw and the respective bushing to which it is attached. This object may be accomplished by turning the end of the reinforcing member inwardly so as to afford a good surface engagement with the bushing and spot welding it thereto. It also may be accomplished by providing a mechanical interlock between the end of the jaw and the bushing, and also by utilizing such an interlock in combination with welding.

In the connectors of this same general type heretofore provided, it has been the practice to form one of the bushings with a closed end. While such a closed end presents certain advantages, these are also attended with some difficulties, particularly in cutting the threads in the bushing. A further object of the present invention is to provide, in a connector of the character aforesaid, a bushing assembly comprising two complementary bushings each of which has a bore extending entirely therethrough with the bore of one of the bushings closed by the end portion of the reinforcing member which may be spot welded thereto. Thus, all of the advantages which attend the initial formation of the bore through the entire bushing are provided while the subsequent closing of the bushing with the end of the reinforcing member provides the closure which is necessary to prevent the molten alloy from flowing thereto during the casting operation.

In the bushing assembly of the application above referred to, a neck is integrally formed with the alloy body of one jaw and this neck

telescopes into a counterbore in the other jaw. This invention presents an improvement over this arrangement in that it has as an object the provision, in a connector of the type noted, of a bushing assembly including a pair of complementary bushings. One of these bushings is formed with a smooth bore, while the other is formed with an extension in the form of a neck which bridges the gap between the jaws and is telescopically received in the smooth bore.

Various other more detailed objects and advantages of the invention such as arise in connection with carrying out the above noted ideas in a practical embodiment will, in part become apparent, and in part be hereinbefore stated as the description of the invention proceeds.

The invention therefore comprises a battery terminal connector which includes a pair of complementary jaws, the main body portion of which is a soft metallic alloy with the free end portions of the jaws having hard metallic bushings imbedded therein, and with a screw stem threaded into the bushings. The jaws are provided with a reinforcing member of U-shaped formation which encircles the battery post opening with each free end anchored to one of the bushings, so as, to prevent excessive pressure on the bushings from rupturing the jaws.

For a full and more complete understanding of the invention, reference may be had to the following description and accompanying drawing wherein:

Figure 1 is a section through a battery terminal connector embodying the improvements of this invention. This view is taken about on the plane represented by the line 1—1 of Figure 2.

Figure 2 is a view in side elevation of the connector shown in Figure 1 with parts broken away and shown in section.

Figure 3 is a detail top plan view, with parts broken away, of one modification of the bushing assembly and reinforcing member.

Figure 4 is a view similar to Figure 3 of another modification, and

Figure 5 is a view showing the reinforcing member in elevation with one of the bushings in section, this view being taken about on the plane represented by the line 5—5 of Figure 4.

Referring now to the drawings wherein like reference characters denote corresponding parts, and first more particularly to Figures 1 and 2, it will be seen that the battery terminal connector of this invention comprises two main parts which are integrally joined together. One of these is the jaw assembly referred to generally by the reference character J and the other the cable anchorage identified in its entirety by the reference character C.

While the cable anchorage C is not particularly pertinent to the present invention, it will be noted that it comprises a cylindrical extension 10 that is formed with a bore 11 and a counterbore 12. A threaded opening 13 is formed in one wall of the extension 10 and communicates with the bore 11.

A sleeve 14 of a metal which is harder than the alloy from which the extension 10 is cast and yet deformable in character, is snugly received in the bore 11. A screw 15 having a head 16 is threaded into the bore 13 and the inner end thereof engages the sleeve 14.

The end portion of a cable (not illustrated) will have the insulation stripped therefrom to bare the wires. These bared wires are received within the sleeve 14 with the insulation being

accommodated by the counterbore 12. The screw 15 may be tightened by using an appropriate tool in conjunction with the head 16 so as to apply pressure on the sleeve 14 which will deform the sleeve and cause it to tightly clamp the bared wires.

The jaw assembly J comprises two complementary jaws 17 and 18. The jaw 17 has a face 19 which is opposed to the face 20 of the jaw 18. This face 19 is formed with a recess 21 while the face 20 is formed with a complementary recess 22. These recesses 21 and 22 cooperate to define the opening which receives the terminal post of a battery, and it will be noted that this opening has a slight taper as shown in Figure 1 to facilitate its being positioned on a battery post.

The jaw 17 has an end portion 23 that is formed with a circular socket 24. Likewise, the jaw 18 has an end portion 25 formed with a circular passageway 26 which extends entirely therethrough, whereas, one end of the socket 24 is closed.

A bushing assembly is referred to in its entirety by the reference character B. This bushing assembly comprises a cup shaped bushing 27 that is received in the socket 24 and which has a closed end as indicated at 28. This bushing 27 has a cylindrical extension 29 which extends beyond the face 19 and at least over to the face 20. The bushing is internally threaded as represented at 30.

At this point, it is well to note that both elements of the bushing assembly B are imbedded in the jaw structure J in such a manner as to be securely anchored therein. For this purpose, the exterior surface of the bushing 27 is formed with ribs such as shown at 31 in Figure 3. It is also important to note that while the main body portion of the bushing 27 is circular in formation, the ribs 31 present an outer contour providing flat faces such as that shown at 32. This flat face 32 has an important function to be later described.

The bushing assembly B also includes a second bushing element indicated at 33. This member is received in the passageway 26 and has external ribs comparable to the ribs 31 which are imbedded in the alloy of the end portion 25 of the jaw 18 and which ribs present a flat surface at 34. The bushing 33 has a smooth cylindrical bore at 35 which is complementary to and telescopically receives the neck 29. It also has an inner threaded section 36. At this point it is well to note that the threaded section 36 of the bushing 33 is of greater diameter than the threaded section 30 of the bushing 27. The importance of this will later become apparent.

A screw stem is referred to in its entirety by the reference character S. This stem includes a threaded section 37 which is complementary to the threads 30 into which it is screwed and which is located at the free end of the stem S. Adjacent to this threaded section 37 is a smooth cylindrical section 38. Adjacent to this section 38 is another threaded section 39 which is complementary to and received in the threads 36.

At this point it is well to note that the threads 30 and 37 assume one direction while the threads 36 and 39 assume the opposite direction. Thus, the threads 37 and 39 are what might be called oppositely threaded sections.

Adjacent to the threaded section 39 there is another smooth cylindrical section 40 which separates this section from a non-circular head 41

which is adapted for engagement by a wrench or suitable tool.

It is notable that the external diameter of the threaded section 37 is at least no greater than the root diameter of the threaded section 39. Thus, this section may be passed through the threads 36 without any engagement therewith so as to permit their being screwed into the threads 30.

In the construction so far described the only bond between the bushings 27 and 33 is that provided by the ribs 31. It has been found from practical experience that if excessive rotative pressure is applied to the screw stem S, it will be transmitted through the threads with such force as to rupture one of the jaws 17 or 18 adjacent to the bushings. In order to prevent this, a reenforcing member is provided. This member is designated 42 and preferably takes the form of a U-shaped band having a width slightly less than the thickness of the jaws so as to permit it to be completely imbedded therein. Due to the U-shaped formation of the reenforcing member 42 there is a bend portion which partially encloses the batter post opening 21-22. One free end of this member 42 is turned inwardly to provide an end flange 43 that engages the surface 32 to which it may be firmly anchored as by spot welding. In a similar manner, the other end of the member 42 is turned inwardly to provide an end flange 44 which engages the face 34 to which it is anchored by spot welding.

Operation

While the operation of the above described connector is believed to be obvious and self-evident from the description already set forth, it may be noted that a cable is first anchored to the cable connection at C in the manner described. The jaw section J is then positioned so that the opening 21-22 receives the terminal post of a battery. An appropriate tool is now applied to the head 41 of the screw stem S and rotated in a proper direction so that the oppositely threaded sections 37 and 39 draw the end portions 23 and 25 of the jaws together. During this action, the neck 29 will telescope into the bore 35.

Should the operator, in his desire to make sure of a firm clamping engagement, apply excessive force to the screw stem S, the reenforcing member 42 will reenforce the jaws 17 and 18 so as to prevent their rupturing under such pressure.

When occasion arises to remove the connector from the battery post, the tool is availed of to rotate the screw stem S in an opposite direction. This provides for a spreading of the jaws with a positive actuation.

First modification

Upon referring to Figure 3, a slightly modified form for one bushing of the bushing assembly B will be described. In this embodiment the cup shaped bushing 27 is replaced by a bushing 45 having a threaded bore 46 extending entirely therethrough. However, after the threaded bore is formed it may be closed by an end portion 47 of the reenforcing member 42 which is spot welded to the end face of the bushing 45. In all other respects, the bushing assembly B and the reenforcing member 42 as well as the jaw structure J and connection C are the same as that described in connection with Figures 1 and 2.

It is notable that the reenforcing member 42 may have a pair of tongues 48 struck from the

bend portion thereof and which tongues are received within the sleeve 14 as is shown in Figure 1.

Second modification

In the embodiment shown in Figures 4 and 5, the ends of the reenforcing member are formed with recesses 49 which receive the circular part of the bushings 27 and 33. These end portions are positioned between the ribs 31 so as to provide a mechanical interlock between the bushings and the reenforcing member. This interlock may be supplemented by spot welding if desired.

While preferred specific embodiments of the invention are hereinbefore set forth it is to be clearly understood that the invention is not to be limited to the exact constructions, devices, and mechanisms illustrated and described because various modifications of these details may be provided in putting the invention into practice within the purview of the appended claims.

What is claimed is:

1. In a battery terminal connector comprising a U-shaped body member of soft metal defining an opening for receiving the terminal post and having a pair of clamping jaws, a bushing and reinforcing assembly embedded in said body member and including axially related bushings of hard metal embedded in said clamping jaws, one bushing having a reduced extension which extends towards the other bushing and being internally threaded for the length of its bore, the bore of the other bushing extending entirely through the same and being internally threaded in its outer length portion, the inner length portion of said last bore opening towards said one bushing and being threadless and of a size as to telescopically receive with sliding clearance the reduced extension of said one bushing, the threads of said bushings being right and left-hand, respectively, a screw stem having right and lefthand threaded sections adapted to cooperate with the corresponding threads of said axially related bushings, and a U-shaped reenforcing member of spring metal partially encircling said opening and having legs permanently affixed at their ends to said bushings.

2. A battery terminal connector as set forth in claim 1, wherein the threaded bore of said one bushing extends entirely therethrough, and the end of one of the legs of said reenforcing member is affixed to the outer end face of said bushing to close the outer end of said bore.

3. A battery terminal connector as set forth in claim 1, wherein the ends of the legs of said U-shaped reenforcing member are each formed with a semi-circular recess adapted to provide a seat for the bushing to which said leg is affixed.
